tion of Delaware

Application December 4, 1939, Serial No. 307,378

7 Claims. (Cl. 96—15)

This invention relates to milling machinery and more especially to machinery for milling out grooves in small work pieces stamped from sheet metal such as for milling grooves in cylinder lock keys.

It is among the objects of the invention to provide a machine of simple and durable construction to be economically manufactured and which will perform milling operations at the minimum cost.

Another object of the present invention is to provide improved means for automatically feeding work pieces to the milling cutters of the machine and removing the milled work pieces from the machine.

Further objects and advantages of the present invention will be apparent from the following description, reference being had to the accompanying drawings wherein a preferred embodiment of one form of the present invention is clearly shown.

In the drawings:

Fig. 1 is a perspective view of the machine taken from the front and right side, the front being that part of the machine directly adjacent the operator who places the work piece blanks in a magazine.

Fig. 2 is a perspective view taken from the rear and one side of the machine.

Figs. 3 and 4 taken together constitute a plan view of the machine.

Fig. 5 located on the same sheet with Fig. 3 is a fragmentary elevational view partly in section. This view is taken looking in the direction of arrow 5 of Fig. 3 and the sectional portion is on the section line 5—5 of Fig. 3.

Fig. 6 which is on the same sheet of Fig. 4 is a sectional view on the line 6—6 of Fig. 4.

Figs. 7 and 8 taken together constitute a longitudinal sectional view through the machine.

Fig. 9 which is on the same sheet with Fig. 7 is a sectional view on the line 9—9 of Fig. 7.

Fig. 10 which is on the same sheet with Fig. 8 is a sectional view of the line 10—10 of Fig. 8.

Fig. 11 is a fragmentary longitudinal sectional view of a portion of the machine shown in Fig. 7 and is drawn to a larger scale than Fig. 7 and shows the blank feeding mechanism in a position of operation different from that shown in Fig. 7.

Fig. 12 is a plan view of a portion of the machine shown in Fig. 7 and is partly in section, that section being taken on the line 12—12 of Fig. 11.

Fig. 13 is a full scale sectional view on the line 55

13—13 of Fig. 7 showing a key blank being operated upon by two milling cutters.

Fig. 14 is a sectional view on the line 14—14 of Fig. 11.

5 Fig. 15 is taken on the line 15—15 of Fig. 12.

Fig. 16 is a sectional view on the line 16—16 of Fig. 12.

Fig. 17 is a sectional view on the line 17—17 of Fig. 12.

10 Fig. 18 is a sectional view on the line 18—18 of Fig. 11.

Fig. 19 is a sectional view on the line 19—19 of Fig. 3.

Fig. 20 is a plan view of a work piece clamping 15 slide.

Fig. 21 is a left end view thereof.

Fig. 22 is a right end view thereof.

Fig. 23 is a plan view of the work piece carrier.

Fig. 24 is a left end view thereof.

Fig. 25 is a sectional view on the line 25—25 of Fig. 23.

Fig. 26 is a plan view of the work piece slide clamp which is to be mounted upon the carrier shown in Fig. 23.

25 Fig. 27 is an edge view of the slide clamp shown in Fig. 26.

Fig. 28 is a plan view of the stationary slide clamp which is to be mounted upon carrier of Fig. 23.

30 Fig. 29 is an edge view of the stationary slide clamp shown in Fig. 28.

Fig. 30 is an edge view of one of the tracks which guide and support the carrier shown in Fig. 23.

Fig. 31 is a left end view thereof.

Fig. 32 is a front face of the work piece ejecting lever.

Fig. 33 is a left end view therefor.

40 Fig. 34 is an elevational view looking in the direction of arrow 34 in Fig. 11 of a bracket for supporting the work piece carrier guiding tracks a portion thereof adjacent the milling cutters.

Fig. 35 is a sectional view on the line 35—35 of Fig. 34.

Fig. 36 is a top plan view of a pressure finger for engaging the movable clamp which laterally engages the work piece, said clamp being shown in Fig. 26.

50 Fig. 37 is an edge view of the pressure finger shown in Fig. 36.

Fig. 38 is an elevational view looking in the direction of arrow 38 of Fig. 12 of a plate for supporting the pressure finger illustrated in Fig. 36.

Fig. 39 is an edge view of the plate shown in Fig. 38.

The machine comprises a base or main frame 40 supported above a floor by legs 41 and 42. Frame 40 supports brackets 43 and 44 including respectively pairs of bearing pedestals 45 and 46. The pair of pedestals 45 is braced by a bar 47 and the pedestal 46 by a bar 48. These bearing pedestals 45 rotatably support a rocker arm 49; and the bearing pedestal 46 rotatably supports a rocker arm 50. These rocker arms 49 and 50 are each fixed to a shaft such as 51 shown in Figs. 3 and 4 in the sectional portion thereof. Shaft 51 is journaled in tapered roller bearings 52 carried by the bearing pedestals 46.

Referring to Fig. 3, the arms 49 and 50 include split tubular portions 53 and 54 respectively with which screws 55 and 56 respectively cooperate to clampingly engage tubular sleeves 57 and 58 respectively. Fig. 5 discloses details of the split tubular portion 53 of the rocker arm 49 and the tubular sleeve 57 mounted therein. Sleeve 57 supports tapered roller bearings 59 which rotatably support a spindle 60. Sleeve 57 is secured to a flange 61 upon which is mounted an electric motor 62, the shaft 63 of which is drivingly connected with the spindle 60. The assembly of sleeve 57, flange 61 and motor 62 may be adjusted axially of the split tubular portion 53 of rocker arm 49 and may be secured in the desired position of adjustment with respect to part 53 by clamping nuts 64 and 65 screw threadedly cooperating with the sleeve 57. In a similar manner the split tubular portion 54 of rocker arm 50 adjustably supports a subassembly comprising sleeve 58, a flange 66 and an electric motor 69 which drives a spindle 70. In Fig. 5 the spindles 60 and 70 are shown, but are broken away in Fig. 3 in order not to obscure certain other parts.

Upon spindles 60 and 70 are mounted rotary milling cutters 71 and 72 respectively which engage a work piece blank such as a key blank indicated by K. (See Figs. 5 and 13.) By a key blank feeding means to be described later the key blank K is positioned between the cutters 71 and 72 while they are separated a distance greater than the thickness of the blank. By a mechanism now to be described the rocker arms 49 and 50 are concurrently operated in opposite directions in order to move the milling cutters 71 and 72 into engagement with the blank K. While the blank K is thus engaged by the milling cutters the blank K is dragged by the key blank feeding means against the action of the milling cutters so that the blank is grooved by the cutters.

The mechanism for oscillating the rocker arms which support the rotating spindles 60 and 70 carrying the milling cutters 71 and 72 will now be described. Referring now to Fig. 4, there is shown a shaft 80 upon which is mounted a groove pulley 81. Pulley 81 receives a V drive belt 82 by which it is connected with the grooved pulley 83 driven by an electric motor 84 mounted on plate 85 supported by the legs of the machine frame. Shaft 80 is supported by bearings 86 and 87 carried respectively by bearing pedestals 88 and 89 integral with a bracket 90 which includes a cover plate 91 for an opening 92 in the right end wall 93 of frame 40 as shown also in Fig. 8. The shaft 80 drives a worm 94 meshing with a worm wheel 95 which is mounted on a shaft 96 supported by bearings 97 and 98 provided respectively by brackets 99 and 100 at-

tached to the frame 40. Shaft 96 drives a cam 101 having a race 102 receiving a roller cam-follower 103 mounted on a pin 104 carried by a slide 105 guided for horizontal movements by brackets 106 and 107 attached to the frame 40. Shaft 96 drives a plate cam 110 carrying on its upper surface a lobe 111 and upon its lower surface a lobe 112. Between the hub 113 of cam 110 and the bracket 100 is located a roller step bearing 114 which transmits the weight of the shaft 96 and parts mounted thereon to the bracket 100 and thence to the frame 40. The upper surface of cam plate 110 and the lobe 111 is engaged by the follower roller 120 mounted upon a rod 121 carried by the lower end of a cylindrical block 122 provided with a notch 123 receiving the roller 120. The block 122 is adjustably mounted in the tubular end 124 of arm 49. The block 122 is secured in the desired position of the vertical adjustment with reference to the tubular portion 124 by nuts 125 and 126 which threadedly engage the block 122. Between the upper end of block 122 and a bracket 127 is located a pressure spring 128 which urges the roller 120 against the cam 110 or its lobe 111. The bracket 127 is supported by the upper end of a pedestal 129 secured to the base 40.

The lower surface of cam plate 110 and the lobe 112 is engaged by roller 130 mounted on rod 131 carried by a cylindrical block 132 received by a tubular end portion 134 of rocker arm 50, said block 132 having a notch 133 for receiving roller 130. Block 132 is attached to the tubular portion 134 in the desired position of vertical adjustment by nuts 135 and 136. The roller 130 is arranged against the roller surface of cam plate 110 and the cam lobe 112 by a spring 138 located in a recess 139 provided by the pedestal base 129 and the frame 40. The cam lobes 111 and 112 are so located that the rocker arms 49 and 50 will concurrently rock in opposite directions simultaneously in order to cause the milling cutters 71 and 72 to engage the key blank K simultaneously.

The mechanism for feeding the work blanks to the milling cutters and for moving them against the cutting action of the cutters will now be described. Referring to Fig. 7 the slide bar 105 which is actuated by the cam 101 of Fig. 8 carries a post 140 having a bifurcated portion 141 screw threadedly connected by screw 142 having shoulders 143 and 144 between which is located a bifurcated extension 145 of a block 146. By turning the screw 142, the block 146 can be adjusted horizontally with respect to the post 140 of the slide bar 105. The screw 142 is secured in the desired position of adjustment by tightening of a clamping screw 147 which forces together the bifurcations of parts 141 in order to clamp the screw 142 under pressure. The head of the screw 147 finds clearance in a groove 148 provided by a bracket 150 (see Fig. 9) and the head of the screw is accessible through an opening 149 of said bracket. Bracket 150 and a similar bracket 151 are supported upon the frame 40 and respectively support rails 152 and 153, rail 152 being shown in detail in Figs. 30 and 31. Rail 152 provides a groove 154 for receiving a tongue 155 provided by the pedestal 150. Rail 152 is provided with holes 158 for receiving screws by which the rail is attached to the pedestal 150. Rail 152 is provided with tapped holes 160 and with a bifurcated lug 162 providing a notch 164. The rail 153 is similarly fashioned but the parts

are reversed since rail 152 is a left-hand member and 153 is a right-hand member, as viewed in Fig. 9.

Block 146 supports the work piece carrier 170 shown in detail in Figs. 23, 24 and 25. Carrier 170 is provided with holes 171 receiving screws by which the carrier is attached to the block 146, said holes being counterbored at 172 to receive the heads of the screws which are not shown. Carrier 170 is guided by rails 152 and 153 and is held thereon by a table plate 260 which is attached to rails 152 and 153 by screws 201, as shown in Fig. 3. The surfaces of rail 152 which support the carrier 170 are indicated at 152a and 152b.

The carrier 170 is provided with a dovetail groove 174 which receives a clamping slide 175, shown in Figs. 29, 21 and 22 where this slide 175 is generally dovetailed in cross section from its left hand edge up to an intermediate edge 176 from which extends a flat extension 177 which is shaped so as to provide inclined edges 178 and 179 for engaging the head of a key which has an octagonal head. The extension 177 is also provided with a notch 180 for receiving an ejector lever to be described later. The extension 177 is received by a groove 181 provided with the carrier 170. The side walls of groove 181 are shaped so as to conform generally to the shape of the work piece blank which is shown as a key blank K in dot-dash lines in Fig. 23. This groove 181 merges with a wide recess 182 for receiving a stationary clamping member 190 having projections 184 for engaging one side of the key blank K. The member 190 is provided with a hole 192 mating with a hole 193 provided with the carrier 170. A rivet 193 passes through the holes 192 and 193 to secure the part 190 within the recess 182 of carrier 170 shown in Fig. 13. The groove 181 merges with a recess 184 for receiving the bifurcation 194 of a movable clamping block 195, shown in Figs. 26 and 27. The other bifurcation 196 of said block 195 is received by a groove 185 provided by the carrier 170, as shown in Fig. 25. That portion 187 located between the grooves 184 and 186 is therefore straddled by the movable clamping block 195 as shown in Fig. 15. The portion 187 is provided with a notch 188 which receives a spring 189 shown in Fig. 15 in order to urge the block 195 in engagement with the rail 152, as shown in Fig. 15, or into engagement with a pressure finger 216, as shown in Fig. 19. The carrier 170 is provided with a groove 72a to provide clearance for the cutter 72 as shown in Fig. 13.

The adjacent bearing pedestals 45 and 46, shown in Fig. 3 provide a support for a mounting plate 211, shown in details in Figs. 34 and 35. A block 212, which is secured to plate 211 by welding, is bifurcated by a notch 213, thus dividing the block into divisions 214 and 215, joined by a web 216 which is triangular in cross section, as seen in Fig. 35. The parts 214, 215 and 216 are welded together. The portions 214 and 215 are provided with tongues 218 and 219 respectively which are received within the grooves 154 and 155 respectively of rails 152 and 153 respectively, said rails being attached to said block portions 214 and 215 by screws which extend through holes 220 and 221 of blocks 214 and 215 and threadedly engage tapped holes in the rails 152 and 153, the tapped holes of rails 152 being shown at 160 in Fig. 30. The block divisions 214 and 215 are each provided with an oval notch 223 to provide clearance for the cutter spindle 70.

The block division 214 which provides the aperture aligned ear 224 carries a pin 225 which pivotally supports an arm 226 shown in detail in Figs. 38 and 39. Arm 226 is provided with somewhat elliptical hole 227 to provide clearance for the cutter spindle 70. Arm 226 is provided with a groove 228 for receiving tongue 229 of pressure finger 210, shown in detail in Figs. 36 and 37. Screws 230 pass through holes 231 in finger 210 and are received by tapped holes 232 in arm 226 in order to secure the pressure finger 210 to the arm 226. Arm 226 is provided with apertures 233 for receiving pins 234 (see Figs. 16 and 19) to limit the movement of arm 226 toward block portion 214. The arm 226 is urged toward the block 214 by two springs 235, each coiled around a screw stud 236 extending through holes 237 provided in both block portions 214 and 215. The stud 236 is screwed into tapped holes 238 provided by the arm 226. The springs 235 are located between the heads 239 of screw studs 236 and the block portion 215. Thus the spring 235 operates through the heads 239 and screw stud 236 to urge the arm 226 counterclockwise, as viewed in Figs. 16 and 19, in order to urge the pressure finger 210 against the movable clamping block 195 and the movable clamping block against the key blank or other work piece K.

During the operation of milling the work piece or key blank K is held down upon its seat provided by the carrier 170 by a roller 240 having ends 241 of reduced diameter received by the notches 164 and 165 of the bifurcated lugs 162 and 163, with which the rails 152 and 153 respectively are provided. The roller 240 is resiliently urged against the key blank K by springs 242 attached, each having one end received by an annular groove in the reduced end 241 of roller 240 and each anchored at the other end to a side bracket member 150 and 151 by a stud 243.

The side brackets 150 and 151 abut spacer blocks 250 and 251 attached to the side brackets by screws or rivets 252 and 253 respectively. Block 250 carries a felt or leather wiper blade 254 which is engaged by the lower edge of block 146 in order to prevent any chips from the milling operation from entering the chamber which houses the pedestal 143 and the slide 165. The side brackets 150 and 151 are tied together at their left hand ends (see Figs. 11 and 12) by a bar 259 attached by screws 260 and 261 respectively to the brackets 150 and 151. The bar 259 carries a screw 262 for engaging a lever 263 as shown in Fig. 11. Lever 263 received within a notch 264, provided by the block 146, is pivotally mounted upon a pin 265 extending across this notch. The upper end of lever 263 is provided with a rounded portion 266, received by an opening 267 provided by the clamping slide 175. When the lever 263 does not engage the pin 262, as shown for example in Fig. 7, a spring 270 received by a recess 271 of block 146 is permitted to act through a plunger 272 to urge the lever 263 clockwise and therefore to urge the clamping bar 175 toward the right in order that it may engage the head of key blank K. Figs. 11 and 12 show the clamping bar 175 in its disengaged position and Figs. 3 and 7 show the clamping bar 175 in its engaged position.

As stated before, the upper surfaces of the rails 152 and 153 support a table 260 upon which may be placed a number of work pieces; such key blanks K are to be stacked by the operator in a magazine which is provided by a vertical pedestal 280 having a groove 281 of such shape as to

maintain the blanks K in proper alignment with the blank conveying apparatus. This pedestal 280 is provided with ears 282 through which screws 283 pass for securing the pedestal 280 to the rails 152 and 153. Holes 284 are provided in the rails for receiving such screws as is shown in Fig. 30. The groove 281 in magazine pedestal 280 opens out upon the table 200 and is closed by a hinged door 285. The pedestal 280 supports a rod 290 shown in Figs. 7, 11 and 12, upon which is mounted an ejector lever 291 urged clockwise by spring 292 which surrounds the stud 293 fixed to the magazine pedestal 280 and having a reduced end extending through a hole in the lever 291. The lever 291 has a pointed arm 294 of such width as to be received by a notch 189 provided in the clamping slide 175 in order that the pointed arm 294 may be permitted to extend down under the key blank K and lift it from the blank conveyor slide 170 during movement of said slide from operating position toward the lever to the non-operating position.

The mode of operation of the apparatus will now be described. Starting with a key blank K in the lowest position in the stack provided by the magazine 289, blank K then rests upon that surface of the carrier 170 which defines the bottom of the groove 181. At the time the blank K drops into this groove the clamping slide 175 has been retracted toward the left, as shown in Fig. 12, in order to allow plenty of clearance around the octagonal head of the key blank. As the shaft 96 rotates the slide 105 moves from left toward right while the milling cutters 71 and 72 remain separated a distance greater than the thickness of the blank K. As the slide 105 and its pedestal 140 move toward the right from the position shown in Fig. 11, the block 146 is caused to move toward the right carrying with it the lever 263 which is moved out of engagement with the screw 262 thereby permitting the spring 270 to actuate plunger 272 to cause the lever 263 to rotate upon the pin 265 clockwise and to move the clamping slide 175 into engagement with the head of the key blank K thereby clamping it within the recess 181 and between surfaces of the carrier 170 and slide 175. As the block 146 continues on with its movement the blank K passes under the hold-down roller 240 and finally the laterally moving clamping block 195 is engaged by the pressure finger 210 and pressure is transmitted to the key blank K from the springs 235 so that, by the time the key blank K has arrived under the milling cutters 71 and 72, it is clamped in three directions, namely (1) longitudinally between surfaces provided by the carrier 170 and the clamping bar 175, (2) laterally between the clamping parts 190 and 195 and (3) vertically between the pressure roller 240 and the carrier 170, all as shown in Fig. 3. Immediately following the location of the key in position for operation upon the cutters 71 and 72, the arms 49 and 50 are engaged by the cam lobes 111 and 112 respectively of the cam 110 and in order to cause the cutters to engage the key and to cut therein the end portions of grooves of the nature indicated particularly in Fig. 13. The cams 110 and 101 rotate clockwise as viewed in Fig. 4. These cams are in such position that the arms 49 and 50 are about to be so rocked upon their pivots that the milling cutters will engage the key blank. As the milling cutters are held in engagement with the key blank while the lobes 111 and 112 are traveling clockwise from the position shown in Fig. 4, the cam 101 will also travel from

the position shown in Fig. 4 and will cause the slide bar 165 to move from right toward left to cause the key to be dragged under the operating milling cutters in order that grooves may be cut therein as shown in Fig. 13. Thus while the key blank is being pulled back toward its original position the milling cutters operate upon it to cut the required grooves.

Shortly after the instant the key blank has been dragged free from the milling cutters, the groove 180 of the clamping slide 175 will have been located vertically under the arm 294 of the ejector lever 291 thereby permitting said pointed arm to be located down under the left hand edge of the key blank K whereupon further movement of the slide 105 and block 146 and carrier 170 toward the left will result in the key blank K being lifted by the ejector lever 291 from the carrier. The key blank K having been lifted from the carrier may be readily swept off from the top of the carrier either by a blast of air from a nozzle, or by pressure of a constantly flowing stream of fluid which lubricates and cools the operating parts, particularly the milling cutters. A continuously flowing stream of liquid has been found satisfactory as it not only sweeps away the finished key blanks but also flushes out chips of material removed by the milling cutters, said chips sliding down the inclined surfaces provided respectively by the blocks 216 and 258, shown in Fig. 11.

While the form of embodiment of the present invention as herein disclosed constitutes a preferred form, it is to be understood that other forms might be adopted, all coming within the scope of the claims which follow.

What is claimed is as follows:

1. In a machine for milling longitudinal grooves in key blanks, the combination of a cutter carrying spindle bodily movable relative to the blank, a blank carrier providing a recess for receiving a key blank; a slide supported on the carrier having jaws for longitudinally gripping the head of the key blank; jaws carried by the carrier for laterally gripping the side edges of the key blank, means rendered effective by movement of the carrier to a position adjacent the cutter spindle for causing the slide to move longitudinally with respect to the carrier and causing the jaws to engage the key blank, and means for ejecting the blank from the carrier during movement of the carrier away from the cutter spindle.

2. In a machine for milling grooves in key blanks, the combination of a cutter carrying spindle bodily movable relative to the blank, a blank carrier providing a recess for receiving a key blank and having jaws for longitudinally gripping the head of the key blank and jaws for laterally gripping the side edges of the key blank, means rendered effective by movement of the carrier to a position adjacent the cutter spindle for causing the jaws to engage the key blank, a hold-down roller under which the blank passes while being operated upon by the cutter, and springs for urging the roller against the blank.

3. In a machine for milling grooves in key blanks, the combination of a cutter carrying spindle bodily movable relative to the blank, a blank carrier providing a recess for receiving a key blank and having jaws for longitudinally gripping the head of the key blank and jaws for laterally gripping the side edges of the key blank, means rendered effective by movement of the carrier to a position adjacent the cutter spindle for causing the jaws to engage the key blank, a

hold-down roller under which the blank passes while being operated upon by the cutter, springs for urging the roller against the blank, and means for ejecting the blank from the carrier during movement of the carrier away from the cutter spindle.

4. In a machine for milling grooves in key blanks, the combination of a cutter carrying spindle bodily movable relative to the blank; a blank carrier providing a recess for loosely receiving a key blank; a slide longitudinally movable with respect to the carrier, said slide having a notch for receiving the head of the key blank; jaws associated with the carrier for gripping the side edges of the key blank; means operable as the carrier moves from its normal position toward the cutter for actuating the slide causing the head of the key to be clamped longitudinally between the carrier and slide; means rendered effective by movement of the carrier to a position adjacent the cutter spindle for causing the jaws to grip the side edges of the key blank; and yieldable means for holding the key blank against rocking as the cutter operates upon the blank.

5. In a machine for milling grooves in blanks the combination of a plurality of cutters bodily movable relative to the blank, a blank carrier including a slide providing a recess for receiving loosely a key blank; means carried by the carrier for actuating the slide longitudinally with respect to the carrier as the carrier approaches the cutters so as to reduce the longitudinal dimension of the recess and clamp the head of the key blank between the slide and carrier, movable jaws adapted for laterally gripping the side edges of the blank; means cooperating with the jaws when the carrier is in a position near the cutters for causing the jaws to engage the key blank; and hold-down means under which the blank passes for maintaining the blank in the recess while the cutter operates upon the blank.

6. In a machine for milling grooves in key blanks, the combination of a cutter carrying

spindle bodily movable relative to the blank; a blank carrier providing a recess for receiving a blank from a magazine from which the blanks gravitate; a slide supported by the carrier and longitudinally movable with respect to the carrier, said slide moving the blank from under the magazine; spring urged means carried by the carrier and operable to move the slide longitudinally in respect to the carrier as the carrier moves from its normal or "home" position toward the cutter, said yieldable means causing the head of the blank to be clamped between the slide and carrier; yieldable jaws carried by the carrier; cam means for actuating the yieldable jaws, to grip the side edge of the key blank as the carrier approaches the cutter; and yieldable means for engaging the top face of the blank so as to prevent the blank from tilting as the cutter operates upon the blank.

7. In a machine for milling grooves in key blanks the combination of a cutter carrying spindle bodily relative to the blank; a blank carrier having a recess for receiving a blank; a slide longitudinally movable in the recess; means pivotally supported on the carrier and coupled with the carrier means cooperating with the slide for holding the slide in one position to permit a key blank to drop by gravitation from a magazine into the recess; spring means for actuating the pivot means so as to move the slide longitudinally relative to the carrier as the carrier moves from its normal position toward the cutter spindle to clamp the blank between the carrier and the slide; resilient jaws associated with the carrier; stationary means for causing the jaws to grip the side edges of the blank as the carrier approaches the cutter spindle; cam means for holding the cutter out of the path of the blank as the blank is moved toward cutter, said cam means permitting the cutter to engage and operate upon the blank incident to the movement of the carrier toward its home position.
